CLAIM

What is claimed is the ornamental design for a hanging plush toy, as shown and described.

DESCRIPTION

FIG. 1 is a top view of the hanging plush toy showing my new design.

FIG. 2 is a left side view thereof.

FIG. 3 is a frontal view thereof.

FIG. 4 is a right side view thereof; and,

FIG. 5 is an underside view thereof.

The design does not include any graphic design placed on the plush toy.
